UNITED STATES PATENT OFFICE.

FRANCIS MARAK, JR., OF EVEREST, KANSAS.

RADIATOR.

SPECIFICATION forming part of Letters Patent No. 451,944, dated May 12, 1891.

Application filed August 1, 1890. Serial No. 360,631. (No model.)

To all whom it may concern:

Be it known that I, FRANCIS MARAK, Jr., of Everest, in the county of Brown and State of Kansas, have invented certain Improvements in Radiators, of which the following is a specification.

My invention has reference to a reducing-drum in which the products of combustion are directed rapidly upward and downward through a series of flues, the course being varied and determined by valves.

The aims of the invention are to simplify the construction and to secure the passage of the currents directly and repeatedly through the drum by one or more of its flues, in order to cause the burning or carrying away of the solid matters which may lodge therein, and thus keep the apparatus clear and in good operative condition.

In the accompanying drawings, Figure 1 is a perspective view of my radiator with portion broken away to show the internal construction. Fig. 2 is a horizontal section of the same midway of its height. Fig. 3 is a view showing the internal partitions removed. Fig. 4 is a horizontal section on the line $x-x$, Fig. 1, looking downward. Figs. 5 and 6 are vertical sections on the lines $x'-x'$ $y-y$, Fig. 2, respectively.

Referring to the drawings, A represents an upright cylindrical body or drum of sheet metal provided at the bottom with an inlet-neck a , through which the products of combustion are admitted into a base-chamber b , lying below the horizontal division c . At the upper end the body is provided with a discharge-neck d and contains a top chamber e , lying above the horizontal division-plate f . The plates c and f are of cast-iron of the full diameter of the drum and fixed in place by bolts or otherwise. The space between these plates is divided by vertical partitions radiating from the center, and hereinafter described in detail, into equal flues or passages 1, 2, 3, 4, and 5. The flue 1 communicates at its lower end directly and constantly with the base-chamber through an opening h . The top of flue 1 is permanently closed by the overlying division-plate; but a lateral opening i leads from its upper end into the top of flue 2, which is provided at its top with the upwardly-opening hinged valve k , operated

by handles k' and affording a direct communication to the top chamber when required. At the lower end flue 2 is permanently closed by the underlying plate, but communicates through opening m with the base of flue 3, which is in turn permanently covered at its top, but provided with a lateral opening o into the top of flue 4. The last-named flue is in turn provided at its lower end with a lateral opening p into flue 5. A hinged valve q , controlled by the protruding handle q' , may be turned, so as to close the top of either flue 4 or flue 5 or leave both open. A hinged valve s , with a handle s' , is located at the lower end of flue 5, and may be turned down to shut off communication with the base-chamber or raised to permit the products to pass directly upward into the flue 5 and also through an opening p into flue 4. A hinged valve t , having a handle t' , serves to open and close communication between the base-chamber and the lower end of flue 3.

The operation is as follows: The valve q being adjusted to close the top of flue 4 and the other valves being closed, the products of combustion ascend from the base-chamber directly into flue 1, and ascending therein escape laterally through the opening into the top of flue 2, in which they descend until they pass through the bottom opening into the flue 3. Ascending in this flue, they pass in turn through the lower opening into the top of flue 4, through which they descend and pass at the bottom into flue 5, through which they ascend into the top chamber, and thence through the delivery-neck at the top. By properly adjusting the valves the course of the products through the apparatus may be materially lessened. When it is desired to give a direct or unobstructed draft, either for the purpose of starting the fire or for the purpose of blowing out and carrying away the soot or other solid matters which may have accumulated, it is only necessary to open all the valves, whereupon the products will ascend directly through flue 1, and pass thence through opening i and valve k . The products entering valve s will ascend in part directly through the valve 5 and in part through the opening p and flue 4 into the top chamber. The products entering past valve t will ascend in part through the valve 2, directly into

the top chamber, and in part through flue 3, and thence through the lateral opening at its top through flue 4. It will be observed that a practically straight or direct passage is thus 5 afforded through each and all of the flues.

In order to reduce the labor of assembling the parts and admit of the partitions being held securely in position, I recommend the construction shown in Figs. 2 and 3, in which 10 the five partitions are formed by three plates. A sheet of metal x , cut away at its corners, as shown, to afford passages between the flues, is bent longitudinally, so as to present a V form in horizontal section and provided with 15 holes $x' x'$. A second plate w , having an indentation in one corner, is bent in like manner and provided with holes $w' w'$. A third and flat plate y is provided with oblique slots y' . Now the angular plates w and x are inserted endwise into the drum, with their angular portions at the center and their outer edges seated against the walls of the drum. The third plate y is inserted into the drum between them, one edge being seated against 25 the wall of the drum, while the other and slotted edge is seated between the angular plates. Bolts z' are inserted through the holes in the angular plates and through the slots of the intervening plates. Before the 30 bolts are tightened the plate y , which was left in an elevated position, is forced downward, when by reason of its inclined slots it is carried outward tightly against the wall of the drum, and also acts on the other end to force

the angular plates in the opposite direction 35 against the drum. In this way the several parts are forced and held tightly to their places. The outer edges of the plates are seated between angular strips z^2 , riveted to the inside of the drum.

Having thus described my invention, what 40 I claim is—

1. The cylindrical body having the top and bottom chambers therein, the division-plates, and the intermediate vertical flues communicating successively at the upper and lower ends, in combination with the two valves at the lower end and the two valves at the upper end.

2. The cylindrical body or shell, in combination with the angular division-plates w and x , the intermediate obliquely-slotted plate, and the connecting-bolts.

3. In a radiator, an upright body divided into a series of vertical flues, said flues communicating successively at the top and bottom to compel a serpentine course of the products of combustion, in combination with top and bottom valves to open the ends of the flues and permit a direct vertical passage of the 55 products through all the flues.

In testimony whereof I hereunto set my hand, this 30th day of October, 1889, in the presence of two attesting witnesses.

FRANCIS MARAK, JR.
